PROTECTIVE DEVICE

Filed Sept. 24, 1930

UNITED STATES PATENT OFFICE

FIELD R. MARINE, OF GARY, INDIANA

PROTECTIVE DEVICE

Application filed September 24, 1930. Serial No. 484,226.

This invention relates to certain novel improvements in protective devices, and has for its principal object the provision of an improved construction of this character which will be highly efficient in use and economical in manufacture.

It is among the several objects of this invention to provide an improved device for protecting a person against hold up or other forms of attack.

Another object of the invention is to provide a device which is particularly adapted for protection against attack in which the arms of the person attacked will be raised since the device is so arranged that the act of the person attacked in raising his or her arms releases a stream of suitable protective gas such, for example, as tear gas.

An additional object of the invention, ancillary to the foregoing object, is to provide a device which is so arranged that when the person held up or attacked raises his or her arms an electric signal alarm may be actuated thereby while a stream of protective gas may be simultaneously released therewith, thereby providing a double protection.

A further object of the invention is the provision of an improved anti-attack device which may be worn under the outer clothing without inconvenience to the wearer so that when the wearer is not in a place where the electric signal actuating means may be connected to an electric alarm the gas protective device embodied in the invention will be available for protection against hold up and other forms of attack.

A still further object of the invention is to provide an improved anti-hold up device which is particularly adapted for the use of persons working in banks and like places.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a perspective view showing the

invention in position to be worn about a person's body;

Fig. 2 is a side elevational view of a preferred form of construction of the gas container and means associated therewith for releasing the gas from the container and the means for actuating an electric signal when the arms are raised into the position of Fig. 1;

Fig. 3 is a sectional detail view taken substantially on the line 3—3 in Fig. 2;

Fig. 4 is a sectional detail view taken substantially on the line 4—4 in Fig. 3; and

Fig. 5 is a sectional detail view taken substantially on the line 5—5 in Fig. 4.

Referring to the drawing wherein the preferred embodiments of the invention are depicted, there is indicated at 10 a body encircling belt or strap from which the invention is supported in a manner to be described presently, and this belt has provided thereon a buckle structure 11. Adapted to extend over the shoulders and to be attached to the belt 10 at both ends thereof are straps 12 and 13 in which are provided buckle structures 14 and 15, it being apparent that the buckles 11, 14 and 15 are intended to permit the straps 10, 12 and 13 to be adjusted in position on the body in the manner depicted in Fig. 1.

Generically indicated at 16 is a gas container. Removably mounted on the container 16 so that the depending flange 17 thereof extends about the walls of the container 16 is a housing 18 on the walls of which are provided spring clips 19 and 20. There are provided on the walls of the container 16 lugs 21 and 22 which are adapted to be engaged by the clips 19 and 20 so as to suspend the container 16 from the housing 18. There is secured to one wall of the housing 18 in any suitable manner a clip 23 which is adapted to engage the strap 10 so as to support the device therefrom as shown in Fig. 2. Secured to the housing 18 by means of screws 24 or the like is a housing 25.

It will be seen, therefore, that the container 16 may be removed from the housing 18 by releasing the spring clips 19 and 20 from the lugs 21 and 22, and this container 16 is adapted to be filled with a suitable protective

gas such, for example, as tear gas, in a manner to be described hereinafter.

Extended around one arm of the wearer of the device is an arm encircling band 26 on which is provided an eyelet 27. Having one end portion attached to the eyelet 27 is a cord 28 which may be of any suitable size and material but is preferably small in diameter and strong. A guiding element 29 is provided on the strap 10 and the cord 28 extends therethrough as shown in Fig. 1. An opening 30 is provided in one wall of the housing 25 and disposed in this opening is a ring 31 which is intended to prevent abrasion of the cord 28. The cord 28 passes through the ring 31 and is wound around a small reel 32. One end of the cord 28 is attached to the guiding flange 52 of the reel 32 as at 53 and this reel is of the spring actuated type so that when the arm of the person wearing the device is raised into position as in Fig. 1 the cord 28 will be unwound from the reel 32 and when the person's arm is lowered the reel will automatically rewind the cord 28.

The reel 32 is rotatably mounted on a shaft 33 which has one end thereof rigidly secured to a sliding plate 34 as at 48. Wound about the shaft 33 and having one end thereof secured to this shaft, as at 50, is a coil spring 51, the other end of which is secured to a guiding flange 52 provided on the reel so as to facilitate guiding the cord 28 about the reel 32. A flange 54 is provided on the reel 32, opposite the flange 52, and secured to this flange 54 by means of screws 55 is a cover plate 56. A collar 57 is provided on the shaft 33 between the flange 52 and the plate 34 and this collar 57 acts as a bearing for the reel 32.

Provided on one end of the plate 34 is an upturned portion which provides the hook 35. Having one end secured to the hook 35 is a coil spring 36, the other end of which is secured to the hooked portion 37 of a plate 38. The plate 38 is attached to the top wall 39 of the housing 18 in any suitable manner such as by soldering. A nose 40 is provided on the plate 34 at the end thereof opposite the hooked portion 35 for reasons to be made apparent hereinafter. Guiding flanges 41 and 42 are provided on the side edges of the plate 38, as best shown in Figs. 2 and 5, and the plate 34 is slidable in these flanges.

There is provided in the top wall 39 of the housing 18 a depression 43 which provides a valve seat for reasons to be made apparent presently. Having the upper end portion thereof slidable in an opening in the seat 43 is a plunger 44 which carries a mushroom plunger head 45. An annular shoulder 46 is provided on the plunger 44 below the valve seat 43 and carried by this shoulder 46 in the bottom side thereof is a ring 47 of insulating material.

Mounted in one wall of the housing 18 in

any suitable manner is a socket 58 which carries arms 59 and 60. A contact 61 is provided on the outer end of the arm 59 and a similar contact 62 is provided on the arm 60. Adapted to be inserted into the socket 58 is a plug 65 to which is attached an electric cord 66 which is intended to be actuated by means of a plug 67 to an electric circuit in which is provided a signal of any approved type, such as a burglar alarm signal.

An annular shoulder 63 is provided on the plunger 44 below the insulating ring 47 and disposed around the plunger 44 below this shoulder 63 is a coil spring 64. The plunger 44 is slidable through an opening 68 in the bottom wall 69 of the housing 18, and through an aligned opening 70 in a plate 71 which is secured to the top wall 72 of the container 16 in any suitable manner. An opening 73 is formed in the top wall 72 of the container. Extending around the periphery of the wall 72 which defines the opening 73 is an annular flange 74 which is provided on a valve housing 75 so as to suspend the housing 75 from the wall 72. A gas valve structure, generally indicated at 76 is provided in the housing 75 and this valve 76 may be of any approved type so as to control the port 79 on downward movement of the plunger 44.

In the present instance, the valve structure 76 is provided with an elongated plunger 77 which is slidable through the cap 78 and the port 79 and this valve plunger 77 carries the valve head 80 which is normally urged into seating position against the valve seat provided by the constricted portion 81 of the barrel 82 by the action of the coil spring 83 which carried the cap 78, it being understood that the barrel 82 is threaded into the housing 75.

A boss 84 is provided on the housing 75 and threaded into this boss, through the wall of the housing 75, is a tubular plug 85 which communicates through an opening 86 with the interior of the housing 75. The plug 85 is threaded exteriorly so as to receive a union 87 which is connected in any approved manner to a flexible gas conducting conduit 88. A perforated member, which in the present instance is in the shape of a star, is connected to the tube 88 at the outer end thereof and this star 89 may be attached to the outer clothing of the user of the device in any suitable manner.

The operation of the device is as follows: The device is intended to be carried beneath the outer clothing of the user, in the manner depicted in Fig. 1, so as to be concealed from view. When the user of the device is attacked, as in a hold up, so that he or she is compelled to raise the arms, it is apparent that the cord 28 will unwind from the reel 32 before the arm carrying the band 26 is freely raised. After the cord 28 has been wound from the reel 32, further upward

movement of the arm carrying the band 26 will act through the cord 28 to pull the slideable plate 34 against the action of the spring 36, so that the nose 40 of the plate 34 will engage the mushroom plunger head 45 to depress the plunger 44 against the action of the spring 64.

The device may be used with or without the cord 66 and attached plugs 65 and 67 but when the cord 66 is connected by means of plug 65 to socket 58 and the plug 67 is connected to a suitable electric signal such as a burglar alarm, the downward movement of plunger 44 will cause the insulating member 47 to engage arm 33 which will engage contact 62 with contact 61 and thereby close circuit to an electric signal device such as those used in banks. In the use of the invention, it is intended that the cord 66 be carried by the user of the device and the cord 66 may be so carried as not to be visible from the front of a cage, counter or the like.

As the plunger 44 is depressed, in the manner described above, it forces the valve stem 77 downward so as to unseat the valve head 80 from the valve seat 81, thereby permitting the gas, such as tear gas, to escape from the cartridge or container 16, through the port 79, through housing 75 and valve barrel 82, through port 86, outlet 85, tube 88 to the star 89 from which the gas will be radiated so as to repel the attacker. It will be seen that downward movement of the mushroom plunger head 45 is limited by the seat 43. Manifestly, any suitable gas may be used in the cartridge 16, and since the cartridge 16 is readily removable from the housing 18 by releasing the clips 19 and 20, the cartridge 16 may be filled and recharged by attaching a gas pressure tank outlet to the plug 85.

When the arm carrying the band 26 is lowered, the spring 51 will rewind the cord 28 onto the reel 32 while the spring 36 will retract the sliding plate 34 so as to disengage the nose 40 from the mushroom plunger head 45 thereby causing the spring 64 to force the plunger 44 upwardly. It is apparent that as the plunger 44 is forced upwardly by the action of spring 64, the spring 83 will force the valve head 80 against the seat 81 to close passage through the valve barrel 82 and thus further escape of gas is prevented. Upward movement of the plunger 44 will likewise release member 47 from arm 60 which will disengage contact 62 from contact 61 and thereby open the circuit to the electric signal alarm with which the device may be associated.

From the foregoing description of the invention it will be seen that I have provided an improved protective device which may be worn comfortably about the person during the daily routine when an electric signal device adapted to be associated with the invention cannot be used, and it will likewise be

seen that the invention provides a double protection when used by persons engaged in banks, and the like, where danger of hold up is frequent.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A protective device for the human person comprising a gas containing cartridge, a valve in the cartridge to control the escape or gas therefrom including a movable element, a slideable member adapted to be engaged with said valve element to move the latter into gas-releasing position, a member rotatably mounted on the slideable member, and a flexible member windable upon the rotative member and having one end attached thereto whereby a pulling force exerted on said flexible member will first rotate the rotative member to unwind the flexible member therefrom whereupon continued force exerted on the flexible member will move the rotative member and the slideable member together therewith and the latter into engagement with the movable valve element to release the gas from the cartridge. 100

2. A protective device for the human person comprising a gas containing cartridge, a valve in the cartridge to control the escape of gas therefrom including a movable element, a slideable member adapted to be engaged with said valve element to move the latter into gas-releasing position, a member rotatably mounted on the slideable member, and a flexible member windable upon the rotative member and having one end attached thereto and the other end attached to a limb of the person whereby a pulling force exerted on said flexible member by movement of the person's limb will first rotate the rotative member to unwind the flexible member therefrom whereupon continued force exerted on the flexible member will move the rotative member and the slideable member together therewith and the latter into engagement with the movable valve element to release the gas from the cartridge. 110

In testimony whereof I affix my signature.
FIELD R. MARINE.
